(57) **CLAIM**

The ornamental design for a table lamp, as shown and described.

DESCRIPTION

FIG. 1 is a front perspective view of a first embodiment of a table lamp showing our design.

FIG. 2 is a front elevation view of the table lamp in FIG. 1.

FIG. 3 is a rear elevation view of the table lamp in FIG. 1.

FIG. 4 is a left side elevation view of the table lamp in FIG. 1.

FIG. 5 is a right side elevation view of the table lamp in FIG. 1.

FIG. 6 is a top plan view of the table lamp in FIG. 1.

FIG. 7 is a bottom plan view of the table lamp in FIG. 1.

FIG. 8 is a front perspective view of the table lamp in FIG. 1, showing the table lamp in a use state after rotation.

FIG. 9 is a front perspective view of a second embodiment of a table lamp showing our design.

FIG. 10 is a front elevation view of the table lamp in FIG. 9.

FIG. 11 is a rear elevation view of the table lamp in FIG. 9.

FIG. 12 is a left side elevation view of the table lamp in FIG. 9.

FIG. 13 is a right side elevation view of the table lamp in FIG. 9.

FIG. 14 is a top plan view of the table lamp in FIG. 9.

FIG. 15 is a bottom plan view of the table lamp in FIG. 9; and,

FIG. 16 is a front perspective view of the table lamp in FIG. 9, showing the table lamp in a use state after rotation.

The broken lines in the figures show portions of the table lamp that form no part of the claimed design.

1 Claim, 16 Drawing Sheets
